UNITED STATES PATENT OFFICE.

FREDERICK A. GUTH, OF WAVERLY, OHIO.

ТИЛТИНГ-ГАТ-ОПЕРАТИНГ МЕХАНИЗМ.

954,280.

Specification of Letters Patent.

Patented Apr. 5, 1910.

Application filed December 21, 1909. Serial No. 534,287.

To all whom it may concern:

Be it known that I, FREDERICK A. GUTH, a citizen of the United States of America, residing at Waverly, in the county of Pike, 5 and State of Ohio, have invented new and useful Improvements in Tilting-Gate-Operating Mechanism, of which the following is a specification.

This invention relates to tilting gate operating mechanism, and has for an object 10 to provide mechanism located at both sides of the gate and in the path of movement of vehicles to be operated by the wheels thereof.

In the drawings, forming a portion of this specification and in which like characters of reference indicate similar parts in the several views:—Figure 1 is a side elevation of a tilting gate showing my improved operating mechanism applied thereto. Fig. 2 is a detail vertical section taken through one of the casings showing the operating mechanism therein. Fig. 3 is a similar section taken on a line at right angles. Fig. 4 is an end view of the gate showing the operating mechanism applied thereto. Fig. 5 is a front elevation of the pitman rod and the sliding member thereon. Fig. 6 is a side elevation of the sliding member and the pitman rod. Fig. 7 is a detail longitudinal 30 section through the upper bar of the gate showing the latch therefor. Fig. 8 is a transverse section taken on the line 8—8 of Fig. 7. Fig. 9 is a fragmentary perspective view of the latch-controlling member.

My improved gate-controlling mechanism is used in the present instance in connection with the form of gate shown in Fig. 1 of the drawings. This gate may be identical in construction with the one shown in my Patent Number 827,630, dated July 31, 1906, or it may be of any suitable well known design. The gate A is operatively connected with a horizontally disposed shaft 1, the said shaft being formed preferably of spring 45 sheet metal of angle iron form. The ends of the shaft are mounted for rotation on posts 2 which are disposed at the sides of the gate and located adjacent to one side of the roadway. Adjacent to each post is a casing 50 3 in which my improved gate-controlling or operating mechanism is housed. The operating mechanism in one casing is identical with the mechanism of the companion cas-

ing and an illustration of one it is thought will suffice for the other. The mechanism 55 consists of a movable member 4 which is somewhat of horseshoe form; it being provided with an opening 5 having a contracted portion 6 which opens into the offset portions 7 formed by the connecting portion 8 at one end of the member. The said member is provided with a pivot bolt 9 which is operatively connected with the casing and with the post. The member is provided with an arm 10 to which is connected 60 the lower extremity of a pitman rod or other equivalent connection 11, the upper end of the said rod being movable in a movable member 12. The member 12 is provided with a bearing 13 in which the portion 14 70 of a crank arm 15 is journaled. The crank arm 15 is operatively connected with the shaft 1 as shown in Figs. 1 and 4 of the drawings.

An actuating member 16 is located outwardly of each casing, the said member being of inverted U-form and as shown in Fig. 3 one arm 17 extends into the casing and is bent upwardly as at 18 and formed with a finger 19 which extends into the opening 5 of the member 4. The member 16 is mounted in any suitable manner for rocking movement but it is held vertically normally by means of a weighted lever 20 which is pivoted in the casing. The free end of the lever has connected thereto one end of a chain 21, the opposite end of the chain being connected with the pin 22 upon the portion 18 of the actuating member 16. The pitman 11 is provided with a series of adjusting openings 23 in which suitably spaced cotter pins or stops 24 and 25 are mounted, the said pins being arranged to limit the upward and downward movement of the member 12, as will be understood.

The top bar B of the gate A is of channel form and mounted on the bar is a movable member 26 which is connected by the member 27 with the shaft 1 so that in movement of the latter the former will be actuated. A latch-controlling rod 28 is revolvably mounted in the channel of the member B and at one end the said rod is formed with a finger 29 and at its opposite end with a similar finger 30. The finger 30 is positioned beneath the portion 31 of a pivoted

latch 32 which is located adjacent to the outer extremity of the bar B and adapted to coöperate with a keeper 33 upon the gate post 34. The member 26 is provided with 6 a finger 35 which extends between the walls of the channel formed by the bar B and as illustrated in Fig. 8 the said finger is disposed immediately beneath the finger 29 of the rock rod 28. When the rock shaft 1 is 10 operated to open the gate the member 26 is actuated to move the finger 35 thereof into engagement with the finger 29 of the rod 28. This movement of the member imparts rocking movement to the rod 28 and through 15 engagement of the finger 30 of the rod with the latch 32 the latter will be actuated and effectively released from its keeper.

The mechanism illustrated in Fig. 2 illustrates that part which is located at the right 20 of Fig. 4 of the drawings, and assuming a vehicle to have engaged the member 26 the said member will be moved to the dotted line position shown in Fig. 2 of the drawings. In this movement of the member 16 25 the finger 19 thereof will engage the walls of the opening 5 to move the member 4 to the position shown in dotted lines in Fig. 2. In view of the connection shown between the crank shaft 15 and the member 4 it will 30 be understood that when the latter is operated as just described rocking movement will be imparted to the shaft 1 and simultaneously with such movement the latch 32 will be released from its keeper and the gate 35 free to move in an open position. When the shaft 1 has been actuated through the medium 40 of the members 4 and 16 the finger 19 of the member 16 will be temporarily locked in the offset portion 7 of the opening 5 and the member 16 will be held in the dotted line position until the gate has swung past the center of gravitation, whereupon, the pitman will be further elevated to actuate the member 4 sufficiently to allow the finger 45 19 to be released from the offset portion 7 of the opening 5. After the finger has been released, the member 16 through the medium of the weighted lever 20 will be again moved to its normal position. After movement of 50 the vehicle past the gate it may be driven across the actuating mechanism at the left end of the part shown in Fig. 4 where the pitman 15 and its connecting part will be

actuated to move the shaft in an opposite direction to that above described.

5t

I claim:

1. In apparatus of the class described, a tilting gate, a movable member, a rock shaft operatively associated with the member to move the same upon movement of the rock 60 shaft, operative connections between the gate and said member, an actuating member connected to move with the rock shaft, means connected with the rock shaft to normally hold its actuating member in an operative position, and means upon the movable member adapted for engagement with the rock shaft to hold it temporarily in a locked position.

2. In an apparatus of the class described, 70 a tilting gate, a rock shaft operatively connected with the gate to impart movement thereto, a crank arm extending from the rock shaft, a movable member, a rock member adapted for operation to impart movement to the said movable member, a pitman extending from the said movable member, and a sliding member on the pitman and operatively connected with the said crank arm.

3. In an apparatus of the class described, 80 a tilting gate, a rock shaft operatively connected with the gate, a movable member, said movable member having an opening formed therein and provided with contracted and with offset portions, connections 85 between the rock shaft and the said movable member, a rock member adapted for cooperation with the said movable member, means for normally holding the said rock member out of engagement with the said 90 movable member, and a finger upon the said rock member adapted when movement is imparted to the said rock member to engage the walls of the opening in the movable member to impart movement to the said 95 member whereby movement will be imparted to the rock shaft, said finger being adapted to be engaged in the offset portion of the aperture to hold the rock member temporarily in a locked position.

In testimony whereof I affix my signature in presence of two witnesses.

FREDERICK A. GUTH.
